UNITED STATES PATENT OFFICE.

LILLIAN C. CALKINS, OF GRAND RAPIDS, MICHIGAN.

STOCKING.

SPECIFICATION forming part of Letters Patent No. 723,361, dated March 24, 1903.

Application filed September 23, 1901. Renewed January 31, 1903. Serial No. 141,368. (No model.)

To all whom it may concern:

Be it known that I, LILLIAN C. CALKINS, a citizen of the United States, residing at Grand Rapids, in the county of Kent and State of Michigan, have invented certain new and useful Improvements in Stockings, of which the following is a specification.

My invention relates to improvements in stockings for children's wear, and more particularly for boys in short pantaloons; and its objects are, first, to provide a stocking with which the back and front of the leg may be interchanged to avert as far as possible wearing them out too rapidly at the knees, and, second, to avert in like manner wearing out the feet and heels. I attain these objects by the construction illustrated in the accompanying drawings, in which—

Figure 1 is an elevation of the stocking as it comes from the machine, and Fig. 2 is the same as it appears upon the foot and leg of the wearer.

Similar letters refer to similar parts throughout both views.

25 A represents the leg of the stocking.

B B represent the feet and heel, forming when not in use a T with the leg.

To prepare the stocking for wear, one of the feet is folded down at the instep (indicated at b) to the point b' and the toe folded up to the point b'', forming the reinforced heel B'. By this construction the foot may be reversed, forming the heel of one foot one

day and of the other foot the next, thus bringing the side a of the leg over the knee one day 35 and the side a' the next day and greatly increasing the wearing qualities of the knees, the foot, and the heel of the stocking and prolonging the life of the stocking fully one half or more. 40

Having thus fully described my invention, what I claim as new, and desire to secure by Letters Patent of the United States, is—

1. As a new article of manufacture, a stocking consisting of a leg having two feet thereon 45 forming a T therewith, substantially as and for the purpose set forth.

2. As a new article of manufacture, a stocking-leg having two feet thereon forming a T therewith, the feet arranged to be folded alternately to reverse the feet and to reinforce the heels, substantially as and for the purpose set forth. 50

3. As a new article of manufacture, a stocking having a leg and two feet forming a T 55 therewith, either of said feet to be folded down, as at b to b', and the toe folded up to b'' to form the convertible reinforced heel B', substantially as and for the purpose set forth.

Signed at Grand Rapids, Michigan, September 21, 1901. 60

LILLIAN C. CALKINS.

In presence of—

W.M. H. CALKINS,

RICHARD W. CALKINS.
